DESIGN FOR A TWISTED MULTIPLE CONNECTER

Ernest Hallewell Cawthra, Menlo Park, N. J., assignor to Phelps Dodge Copper Products Corporation, New York, N. Y., a corporation of Delaware

Application January 15, 1938, Serial No. 74,312

Term of patent 14 years

To all whom it may concern:

Be it known that I, Ernest Hallewell Cawthra, residing at Menlo Park, in the county of Middlesex and State of New Jersey, have invented a new, original, and ornamental Design for a Twisted Multiple Connecter, of which the following is a specification, reference being had to the accompanying drawing, forming part thereof,

The figure shows the article, embodying my new design.

The device appears substantially the same from the opposite side.

I claim:

The ornamental design for a twisted multiple connecter as shown and described.

ERNEST HALLEWELL CAWTHRA,
